UNITED STATES PATENT OFFICE.

KARL B. NARANS AND GEORGE R. GAMPHER, OF ELDORADO, ILLINOIS.

COMBINED LIGHTNING ARRESTER AND CHOKE COIL.

Application filed February 18, 1921. Serial No. 445,960.

To all whom it may concern:

Be it known that we, KARL B. NARANS and GEORGE R. GAMPHER, citizens of the United States, residing at Eldorado, in the county of Saline and State of Illinois, have invented certain new and useful Improvements in a Combined Lightning Arrester and Choke Coil; and we do hereby declare the following to be a full, clear, and exact description of the invention, such as will enable others skilled in the art to which it appertains to make and use the same.

In recognition of the fact that, in the use of distributing transformers as at present employed and installed, the breaking down, puncturing or burning out of the coils, due to an overload, such as lightning or other static discharge, occurs in the first ten or twelve convolutions of the coil, it is an object of the invention to arrange a protective or choke coil in such relation to and outside of the transformer as to absorb the energy of the overload or excessive charge and prevent it from reaching the coil of the transformer, and more especially to combine or associate such a protective or choke coil with a lightning arrester in a common or unitary apparatus or appliance for arrangement between the line and the transformer, so that the positioning of the lightning arrester will be accompanied by the proper location in reference thereto and with reference to the transformer of the choke coil, and so that the cost of constructing and installing the choke coil may be minimized, and materially reduced from that which is involved in the independent construction and mounting or installing thereof, and in carrying out this object the choke coil feature, of which a typical form is illustrated in the accompanying drawing, is associated with a lightning arrester of a commercial form well known upon the market as the General Electric compression chamber type, and is so related with the arrester as to adapt it to be constructed therewith as a unitary device designed to be installed in one operation under conditions precluding the possibility of an improper or ineffective relative arrangement.

In the drawings:

Figure 1 is a side view of an apparatus embodying the invention.
Figure 2 is a vertical sectional view of the same.

Figures 3 and 4 are opposite end views of the device.

Figure 5 is a cross section on the plane indicated by the line 5—5 of Figure 2.

The casing of the device in the illustrated embodiment consists of tubes 10 and 11 of porcelain or like insulating material embedded at their lower ends in a base 12 also preferably of porcelain or the like and covered by a common cap 13 of the same material, said tubes being set in the base and cap in a cement compound as indicated at 14 and 15 with a metallic cap 16 closing the upper ends of the tubes and housed within the insulating cap.

In the tube 10 is arranged the resistance rod 17 of the type of lightning arrester above mentioned, together with the metallic electrodes 18 spaced by insulating rings 19 to form spark gaps with the conductor 20 at the lower end of the series connected with the ground lead 21, while attached to the metal cap 16 is a terminal 22 for the connection of the line lead 23.

The choke coil 24 having any desired number of convolutions is connected at its upper end to the metallic cap so as to be in connection therethrough with the terminal 22 and is provided at its lower end with the terminal 25 with which is connected the transformer lead 26.

Thus there is arranged in a common device of unitary construction a combined lightning arrester and choke coil, adapted to be installed or secured in operative position by a single operation with the elements thereof properly located with reference to the transformer and with the choke coil between the arrester and the transformer with the arrester on the line side of the coil, and with the coil presenting a sufficient number of convolutions outside of or in the path of approach to the transformer to absorb any overload to prevent the burning out or puncturing of the transformer coil, while said choke coil acts to choke back lightning and cause it to pass through the arrester to the ground.

Obviously the gage of the wire forming the choke coil may be varied to suit the load under which the apparatus is to be placed while the combination with the choke coil of the arrester eliminates the hazard incident to the use of the ordinary choke coils now in use by reason of the fact that it is

enclosed in a porcelain or like insulating tube.

Having thus described the invention, what we claim is:—

- 5 1. A device for the purpose specified having tubes one containing lightning arresting means and the other containing a choke coil provided with the same line terminal, the lightning arresting means having a terminal adapted to be connected to ground and the coil having a terminal adapted to be connected to a transformer terminal.
- 10 2. A device for the purpose specified having parallel tubes of insulation, a base and a closure cap common to said tubes, a terminal cap common to said tubes adapted to be connected to the line, lightning arresting
- 15

means including a resistance rod and spark electrodes arranged in one of the tubes and a choke coil arranged in the other tube and 20 in connection at one end with said terminal cap, the lightning arresting means having a separate terminal adapted to be connected to the ground and the choke coil having a separate terminal adapted to be connected to 25 a transformer lead.

In testimony whereof we affix our signatures in presence of two witnesses.

KARL B. NARANS.
GEORGE R. GAMPHIER.
